(57) **CLAIM**

The ornamental design for a vehicle headlamp, as shown and described.

DESCRIPTION

FIG. 1 is an outer perspective view of vehicle headlamp showing our new design;

FIG. 2 is a front view thereof;

FIG. 3 is a rear view thereof;

FIG. 4 is a side view thereof;

FIG. 5 is a top view thereof; and,

FIG. 6 is a bottom view.

It will be understood that the broken lines shown in the drawings illustrate portions of the vehicle headlamp that form no part of claimed design.
